UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,231,912.

Specification of Letters Patent. Patented July 3, 1917.

Application filed January 25, 1915. Serial No. 4,100.

To all whom it may concern:

- Be it known that I, GEORGE P. KINGSBURY, a citizen of the United States, residing at Brooklyn, in the county of Kings and State of New York, have invented certain new and useful Improvements in Typographical Machines, of which the following is a specification, reference being had thereto in the accompanying drawing.
- 10 My invention relates to typographical machines, such as linotype machines of the general organization represented in U. S. Letters Patent, No. 436,532, to O. Mergenthaler, wherein circulating matrices are released from a magazine in the order in which their characters are to appear in print and then assembled in line, the composed line transferred to the face of a mold, the mold filled with molten metal to form a 15 slug or linotype against the matrices which produce the type characters thereon, and the matrices thereafter returned through distributing mechanism to the magazine from which they started.
- 20 Ordinarily, these machines are equipped with a so-called font-distinguisher which is located in the distributor box just in advance of the distributing mechanism proper and serves to prevent delivery thereto of 25 matrices of improper font. In the use of such distinguisher, however, the presence in the composed line of such a matrix is not detected until after the casting operation has been effected, with the result that the 30 slug bears a type character of wrong font and consequently must be discarded and a new slug cast in place thereof. This is not only annoying but occasions an unnecessary waste of time. In addition, in order to 35 move the offending matrix, the operator is compelled to leave his seat at the keyboard, and pass to the rear of the machine, where he will be within reach of the distributor box.
- 40 To overcome these various objections, I propose to locate the font-distinguisher at some point in advance of the casting mechanism, so that the presence of a foreign matrix may be detected before the casting takes 45 place. Preferably, I mount the distinguisher on the assembler, wherein the line is composed, so that when the improper matrix is detected, it may be readily removed and without requiring the operator to leave his 50 seat at the keyboard. I also propose to em-

ploy an arrangement of some suitable character which will direct the attention of the operator to the presence of the improper matrix when it is detected. In one of the forms herein shown, I have provided locking means which, when a matrix of wrong font is present in the composed line, arrests the upward movement of the assembler and thus prevents the delivery of the line to the transfer devices which carry it forward for casting. In another form, I have provided an alarm which will be operated under similar conditions, as the elevator is raised. Other objects and the means for attaining them will later be described and finally 60 65 70 75 80 85 90 95 100 pointed out in the claims.

In the accompanying drawings, I have shown my invention only in preferred form and by way of example, and as applied to a linotype machine, but obviously many changes and variations may be made therein, and in its mode of application, without departure from its spirit. Generally speaking, I desire it to be understood that I do not limit myself to any specific form or embodiment, except in so far as such limitations are specified in the claims.

Referring to the drawings:

Figure 1 is a front view of a portion of a linotype machine having my invention applied thereto;

Fig. 2 is a section on the line 2—2 of Fig. 1;

Fig. 3 is a partial horizontal section, showing the presence of an improper matrix in the composed line;

Fig. 4 is a view similar to Fig. 2, showing the elevator in course of normal ascent;

Fig. 5 is a sectional front view showing the elevator arrested in its ascent;

Fig. 6 is an end view of the assembler, partly broken away;

Fig. 7 is a detail showing the matrices assembled at different levels; and

Fig. 8 illustrates a modification.

I have shown herein only such parts of a linotype machine as are concerned with my present invention. The other parts may be of the usual construction as embodied in the commercial linotype machine or as illustrated in the patent before mentioned.

The matrices X as they are released from their magazine pass onto the traveling belt A, which delivers them to the assembler B wherein they are composed side by side in 110

line. The assembler is thereafter raised and delivers the composed line to the carriage C, which transfers it endwise through the intermediate channel D for presentation to the mold, all as well understood in the art. The assembler B is provided as usual with two movable blades b and b' , the latter arranged at the receiving end in position to arrest the descending matrices at their higher level, at which they are supported by the other blade b . The assembler is also provided with the customary swinging gate B', whereby access may be had to the line when desired.

According to my present invention, I provide the assembler B with a font-discriminator which may coöperate with the matrices during or after composition and detect the presence of one of improper form or font. In the present instance, the discriminator is in the form of a plate E extending throughout the length of the assembler and attached by means of a screw E' to an overlying bar F, which latter is carried at its opposite ends by a pair of arms F' pivoted, as at F², to the side members of the gate B'. The arm F' at the right has a downward extension F³ carrying at its lower end a roller F⁴, which tracks upon an inclined surface G' formed on a bracket G attached to the framework of the machine. The other arm F' of the bar F is provided with a roller F⁵ arranged in engagement with a leaf spring F⁷ on the elevator, the spring tending normally to move the bar F and the attached plate E inwardly toward the matrix line. However, the roller F⁴ on the downward extension F³ will engage the inclined surface G', when the assembler is in its lowermost or normal position and hold the plate E away from the matrix line, as indicated in Fig. 2. The effect of this arrangement is that the plate E will be moved toward and from the matrix line as the assembler is raised and lowered, respectively.

The matrices X of a given font are each provided in one of their vertical edges with two notches α , which notches are adapted to register horizontally when the matrices are composed in line. The purpose of the duplicate notches is to allow the matrices to be assembled at two different levels in the line, in which event the lower notches of the matrices at the upper level will register with the upper notches of the matrices at the lower level, as shown for example in Fig. 7.

It is pointed out that the vertical position of the plate E is such that when moved inwardly by the rocking of the bar F it will enter the aligned notches α of the matrices. It follows, therefore, that if there be present in the composed line a matrix without such notch, or one whose notch does not register with those of the other matrices

(Fig. 3), the inward movement of the plate E will be arrested or prevented and the presence of the offending matrix thus detected.

I also provide means to arrest the upward movement of the assembler when the plate E is held against inward movement by an improper matrix. To this end, the extension F⁸ is formed with a laterally projecting lug F⁶, which is adapted to coöperate with a shoulder G² on the bracket G, the lug F⁶ and shoulder G² being so located as to stand in vertical alinement when the plate E is in its normal position away from the matrix line. As a result, if the plate E is maintained in this position, by reason of the presence of a foreign matrix, these parts will engage and arrest the assembler when it is attempted to raise it for the transfer of the line, as shown in Fig. 5. If, however, the matrices of the composed line are of the same font and in proper order, all their notches will align and allow the plate E to be moved inwardly thereinto. In this event, the lug F⁶ will be moved out of register with the shoulder G² so as to clear it and allow the assembler to be raised in the regular way, (Fig. 4).

The general operation of the parts will be clear from the foregoing description, and it suffices to say at this point that the initial upward movement of the assembler will automatically effect the movement of the plate E inwardly toward the composed line to detect a foreign matrix therein, and that the further movement of the assembler will depend upon the presence or absence of such a matrix. In this manner, the operator is advised as to the constitution of the line, and may proceed to correct it, if necessary.

In Fig. 8 I have shown, as an alternative construction, an alarm to indicate the presence of the improper matrix. In this figure, the lug F⁶ on the extension F⁸ is adapted to engage a spring-pressed arm H carrying at its outer end a striker H' for a bell H². According to this arrangement, when the plate E is held against inward movement by an offending matrix, the raising of the assembler causes the lug F⁶ to engage the arm H and move the striker H' to active position, it being released when the lug passes the arm in the continued movement of the assembler. The striker then sounds the alarm and notifies the operator.

It will be understood that different fonts of matrices will be formed with differently located notches. I therefore mount the plate E so that it may be adjusted vertically to different positions to correspond to the location of the notches in the matrices of one font or another. In this connection, it will be noted that the screw E', previously referred to, passes upwardly through an opening in the bar F and is provided at its outer end with an adjustable nut E², which bears

upon the upper face of the bar, and, as shown in Fig. 1, that the plate E is provided at its opposite ends with a pair of guiding studs E⁴ fitting in sockets in the bar F, the studs being surrounded by spiral springs E⁵ which tend normally to urge the plate downward. It will be seen, therefore, that by turning the nut E² in one direction or the other, the plate E may be raised or lowered to the desired position. An indicator I may be employed to assist the operator in effecting the proper adjustment of the plate.

In order that the spacers Y will not interfere with the detecting movement of the plate E, I form each of them with a cut or notch y of a depth corresponding to that of the notches in the matrices and of an extent sufficient to accommodate the plate in any of its different vertical positions.

As before pointed out, the bar F which carries the distinguisher plate E is connected to the swinging gate B'. As a result of this arrangement, the gate and its connected parts are free to be swung downwardly in the usual way to give access to the matrix line, as shown for example in dotted lines in Fig. 6. The customary spring F⁷ presses against the roller F⁶ on one of the arms of the plate F and serves to hold the gate in its proper position, just as heretofore.

As previously stated, I have shown my invention merely in preferred form and by way of example, and it will be obvious that many modifications and alterations therein will suggest themselves to those skilled in the art, and still be comprised within its scope.

Having thus described my invention, its construction and mode of operation, what I claim and desire to secure by Letters Patent of the United States, is as follows:

1. In a typographical composing and casting machine, the combination of an assembled group or line of type or matrices varying in form as to font, and means located in advance of the casting point to detect the presence in the group or line of a type or matrix of improper font.

2. In a typographical composing machine, the combination of an assembler wherein the type or matrices are composed, and means mounted on the assembler to detect the presence of an improper type or matrix therein.

3. In a typographical composing and casting machine, the combination of a plurality of fonts of type or matrices each formed with a notch, the notches of one font being located in a different position from those of another font, and a font-distinguisher located in advance of the casting point and adapted to enter the notches of the type or matrices of one of said fonts and adapted to be engaged by a type or matrix of the

other font, whereby the presence of the latter will be detected.

4. In a typographical composing machine, comprising type or matrices each formed with a notch, the combination of an assembler wherein they are composed, and a font-distinguisher mounted on the assembler and adapted to enter the notches in the type or matrices; whereby type or matrices of unlike form will engage the distinguisher and their presence be thus detected. 70

5. In a typographical composing machine, the combination of a movable assembler wherein the type or matrices are composed in line, and means controlled by an improper type or matrix in the line to arrest the movement of the assembler. 80

6. In a typographical composing machine, the combination of a movable assembler wherein the type or matrices are composed in line, a font-distinguisher thereon to detect the presence of an improper type or matrix therein, and means controlled by the distinguisher for arresting the movement of the assembler. 85

7. In a typographical composing machine, the combination of a movable assembler wherein the type or matrices are composed in line, a font-distinguisher thereon movable to detect the presence of an improper type or matrix therein, and means whereby the movement of the assembler will effect the movement of the font-distinguisher. 95

8. In a typographical composing machine, the combination of a movable assembler wherein the type or matrices are composed in line, a font-distinguisher thereon movable to detect the presence of an improper type or matrix therein, means whereby the initial movement of the assembler will effect the movement of the distinguisher, and means controlled by the distinguisher for preventing the further movement of the assembler. 100

9. In a typographical composing machine, the combination of a vertically movable assembler wherein the type or matrices are composed in line, a font-distinguisher thereon, and automatic means for moving the distinguisher into and out of the path of the type or matrices as the assembler is raised and lowered, respectively, for the purpose described. 115

10. In a typographical composing machine, the combination of an assembler wherein the type or matrices are composed in line, a font-distinguisher to detect the presence of improper type or matrices therein, and means controlled by the distinguisher to indicate such detection. 120

11. In a typographical composing and casting machine, the combination of an assembled group or line of type or matrices, a font-distinguisher located in advance of the casting point to detect the presence of 130

an improper type or matrix therein, and means controlled by the distinguisher to indicate such detection.

12. In a typographical machine, the combination of a plurality of fonts of type or matrices each formed with a notch, the notches of one font being located in a different position from those of another font, a part through which an assembled group or line of such type or matrices pass, a plate mounted on said part to coöperate simultaneously with all the matrices of the assembled group or line, the said plate being movable into the notches of the matrices of one font and adapted to be held against such movement by its engagement with a type or matrix of another font.

13. An assembler for typographical composing and casting machines wherein the type or matrices are composed in line before casting, and provided with a font distinguisher to detect the presence in the line of an improper type or matrix.

14. In a typographical composing machine, the combination of an assembler wherein the type or matrices are composed, a font-discriminator thereon, and means for adjusting the font-discriminator to different positions to correspond to one font or another, as required.

15. In a typographical composing machine, the combination of an assembled group or line of type or matrices, a font-discriminator to coöperate with the assembled group or line in advance of the casting point, and means for adjusting the discriminator to different positions to correspond to type or matrices of different fonts.

16. In a typographical composing machine, the combination of the movable assembler B, the movable plate E to detect type or matrices of improper form, the pivoted arm F¹ for moving said plate and provided at its lower end with the lug F⁵, and the shoulder G² on the framework of the machine to coöperate with the lug.

17. In a typographical composing machine, the combination of the movable assembler B, the movable plate E to detect type or matrices of improper form, the pivoted arm F¹ for moving said plate and provided at its lower end with the roller F⁴, and the inclined surface G¹ on the fixed framework of the machine to coöperate with the roller, in the manner described.

18. In a typographical composing machine comprising type or matrices, each

formed in one of its vertical edges with two notches, the combination of an assembler provided with means for supporting the type or matrices at two different levels, the upper notches of the matrices at the lower level registering with the lower notches of the matrices at the upper level, and the plate E mounted on the assembler and adapted to be moved into the notches when in proper alignment.

19. In a typographical composing machine comprising type or matrices and justifying spacers, the combination of an assembler wherein they are composed in line, and a plate mounted on the assembler and movable transversely of the line, both the matrices and spacers being formed with notches in their edges to permit such movement.

20. In a typographical composing and casting machine, the combination of an assembled group or line of type or matrices, a font distinguisher to detect the presence of an improper type or matrix in the line, and means controlled by said distinguisher to prevent the delivery of the assembled group or line to the casting mechanism.

21. In a typographical composing and casting machine, the combination of a movable part to carry an assembled group or line of type or matrices, a font distinguisher to detect the presence of an improper type or matrix in the line, and means controlled by said distinguisher to prevent the movement of said part.

22. In a typographical composing and casting machine capable of handling type or matrices varying in form as to font, the combination of mechanism for assembling such type or matrices in line preparatory to casting, and means associated with the assembling mechanism to detect the presence of a type or matrix of improper font, for the purpose described.

23. In a typographical composing and casting machine, the combination of a font distinguisher located in advance of the casting point to detect the presence of an improper type or matrix, and means controlled by the font distinguisher to indicate such detection.

In testimony whereof, I have affixed my signature in presence of two witnesses.

GEORGE P. KINGSBURY.
